UNITED STATES PATENT OFFICE.

WILLIAM ARTHUR RANKEN MICHAEL McRAE, OF LONDON, ENGLAND.

METHOD OF AND APPARATUS FOR REDUCING FIBROUS MATERIAL.

1,184,112.

Specification of Letters Patent.

Patented May 23, 1916.

Application filed June 7, 1913. Serial No. 772,396.

To all whom it may concern:

Be it known that I, WILLIAM ARTHUR RANKEN MICHAEL McRAE, a subject of the King of England, residing in London, England, have invented certain new and useful Improvements in Methods of and Apparatus for Reducing Fibrous Material, of which the following is a specification.

This invention relates to improvements in a method of and apparatus for treating bamboo and like material and has particular reference to the preliminary treatment of such material prior to its utilization for the production of papermakers' half-stuff, paper pulp or paper. More particularly the apparatus is employed for reducing or disintegrating material and has for its object to carry out such reduction or disintegration without damaging the fiber.

The present invention consists broadly in a method of reducing material of the kind described to separated fibers or separated groups of fibers by the subjection of the culms or stalks of the material to a simultaneous rubbing and crushing action characterized by the application of that compound action to virtually all the different portions of the length of a culm or stalk at the same time.

Apparatus for carrying the invention into effect comprises means simultaneously to rub and crush the culms or stalks and to apply that compound action to virtually all the different portions of the length of the culm or stalk at the same time.

A preferred construction of apparatus for carrying the invention into effect comprises two or more rotating rolls of differing speeds with or without feeding devices to deliver the culms or stalks to the rolls with the lengths of the culms or stalks parallel or virtually so with the lengths of the rolls. Such an apparatus also preferably includes means to permit relative adjustment between the co-acting surfaces of the rolls.

The invention also includes a feeder device adapted to regulate the charges which it delivers to the reducing apparatus with or without means coöoperating with a feeder and operated by a charge to prevent the delivery of that charge when the quantity thereof exceeds predetermined limits.

There may also be combined with the apparatus a reducing feed having a support for the material and a member coöperating therewith to reduce the depth of the material on the support over and above a predetermined minimum. Such a reducing feed may conveniently comprise two rotating members having their peripheries separated, or channelled, the serrations in one member forming supporting surfaces for the material, the minimum distance between the centers of rotation of the two members being fixed while movement between them in opposite directions is resiliently controlled.

The invention also includes the product derived from the apparatus.

Other features of the invention will be more clearly understood from the following description taken in connection with the accompanying drawings which illustrate a preferred embodiment of the invention, and in which—

Figure 1 is an elevation of the machine; Fig. 2 is a plan view of the machine illustrated in Fig. 1; Fig. 3 is a perspective view of the feed mechanism, and Fig. 4 is a diagrammatic illustration of a part of the machine showing the doctors and reducing rolls.

The apparatus may be roughly considered under three different headings:—(1) Preliminary feeding apparatus. (2) Combined feeding and reducing apparatus, and (3) Reducing apparatus proper.

The apparatus under heading No. 1 in the embodiment illustrated comprises an endless band, chain or the like A passing at one end over a sprocket or similar member A¹ and having projections extending radially therefrom as at A² which may be conveniently formed of angled metal strips riveted to the endless band A or otherwise conveniently secured thereto. The distance between each projection or partition A² measured longitudinally of the band is such as to determine roughly the quantity of material to be carried between each partition. Thus the bamboo or like material may be fed into it in any desired manner and the apparatus will hereinafter be described in connection with the treatment of

bamboo, although it is to be understood that the invention is not limited to this particular class of material, and wherever mention is made of it, such mention applies 5 equally to canes or other like material.

The bamboo may be preferably preliminarily treated as by cutting into lengths or by removing the knots or nodes, although this latter step is not essential. The 10 veyer band A is caused to travel with a speed which will feed the bamboo to the apparatus under the second heading referred to above at the required rate, that is to say, the bamboo contained between any two partitions 15 A² is shot out into the second portion of the apparatus at predetermined time intervals. Combined with the feed carrier A, and disposed above it at its discharge end, is a trip gear composed of an arm B rigidly secured 20 to a bracket B¹ which pivots at B² on a support B³ and has sliding engagement as by means of the bolt B⁴ with a groove B⁵ in a member B⁶ capable of sliding on a shaft B⁷ but being feathered or otherwise secured 25 thereto so that the shaft B⁷ and the member B⁶ are incapable of rotating independently of one another. The shaft B⁷ is an extension of, or is connected with, a roller A⁸ which carries the endless band A at one extremity, 30 while a roller A⁴ carries it at the other extremity. The shaft B⁷ also carries the member A¹ which has grooves adapted to coöperate with the partitions A² to cause the band A to be rotated as the shaft B⁷ is rotated. 35 A pinion B⁸ is mounted on the shaft B⁷ and is capable of freely rotating thereon, and meshes with another pinion B⁹ which is driven as will be more particularly described hereinafter. A projection B¹⁰ from the pinion forms a clutch tooth to engage in a 40 clutch slot B¹¹ in the member B⁶ so that the shaft B⁷ may, by this means, be normally coupled to the pinion B⁸ to be rotated by it, and when the material contained between 45 any two of the partitions A² exceeds a certain predetermined maximum, it may engage with the arm B to move it so as to throw out the clutch B¹⁰, B¹¹, and thus stop the feed of the material to the machine. 50 Obviously a space between two partitions A² may contain one stem of comparatively large diameter or two or more smaller stems and these may be piled one on the other but are fed on to the carrier A so that the run of 55 the fiber is transverse to the length thereof.

The second portion of the apparatus comprising a reducing feed consists of two fluted or channeled rolls C C¹ disposed one above the other so that the upper one is not perpendicular 60 above the lower one but is a little to the rear of it considered in the direction of travel of the bamboo through the machine. These rolls preferably have eight deep channels and are so arranged that their 65 teeth mesh with one another as they are ro-

tated. At the bottom of each channel there may be, if desired, cast on or otherwise secured in place a ridge extending axially of the roller C or C¹ which ridge may be triangular in section having its apex arranged to 70 contact with the bamboo to aid in splitting it. The lower roll preferably rotates in stationary bearings which, for the sake of clearness, are not particularly illustrated in the drawings, while the upper one rotates in bearings 75 C² sliding in guides C³ so that it is movable toward or away from the lower roll. The minimum distance between the axes of the rolls is fixed by a stop C⁴ while movement to increase the distance between the axes may 80 be carried to any required degree, preferably against the action of springs C⁵ or other resilient controlling members, such as hydraulic, pneumatic, india rubber, or like controls. The action of the springs may be varied by 85 means of bolts C⁶ passing centrally therethrough and at one end engaging the bearings C² and at the other end by means of a washer C⁷ engaging the spring C⁵. The first carrier A is so arranged in its movement and 90 is so positioned in relation to the lower reducing feed roll C¹ that the material contained between two partitions in the first-mentioned carrier is discharged into one of 95 the channels in the roll C¹ and the material carried between succeeding partitions is discharged into succeeding channels of the roll C¹. It is then carried around by the roll C¹ until the projection from the roll C comes 100 into crushing contact with it. The distance 100 between the extremity of a tooth in the roll C is such that on the material of a certain predetermined size or smaller, no crushing action is effected, while material larger than that particular size will be crushed. 105

The material thus treated is then carried around by the channel in the roll C¹ to the apparatus utilized under the third heading. Such apparatus may be considered as the reducing apparatus proper, and consists of 110 a series of rolls carried on shafts D, D¹, D², D³, D⁴ respectively, and referred to as D¹⁰, D¹¹, D¹², D¹³ and D¹⁴. The distance between the centers or axes of adjacent pairs of rolls progressively diminishes through 115 the series and each of the shafts D-D⁴ is carried in bearings capable of adjustment relatively to the adjacent rolls. In connection with the rolls D¹³ and D¹⁴ these bearings have been shown at D⁵ and D⁶ as sliding 120 between guides D⁷ forming part of the framework of the machine and similar bearings are provided for the other rolls. The pair of rolls nearest the reducing feed C C¹ are arranged in relation thereto so that the 125 material is discharged from a channel in the roll C¹ into a space between the first two rolls D¹⁰ and D¹¹. It is then carried by the two rolls into the space between them and as the speed of each roll through the 130

machine progressively increases, the material is subjected to a combined crushing and shearing action between each pair of rolls through which it passes. It will be at once seen that the shearing action is produced mainly by friction as distinct from a cutting action and the combined action of a pair of rolls may be termed a "rub-crush" or "shear-crush" action. After it has passed through the "nip" (that is the space between them across which an imaginary line joining the axes of the two rolls would pass) it is brought on to a support or doctor E extending the length of the roll which is spaced from the roll at the same or greater distance than the "nip" between the two rolls. Such a doctor or support E is provided between each pair of adjacent rolls and is so arranged that one edge acts as a doctor or scraper in connection with one of a pair of adjacent rolls which is rearmost considered in the direction of travel of the material through the machine.

The doctors E may be curved plates or castings adjustably mounted so as to accommodate any adjustment of their respective rolls and as the material passing on to these will not be further compressed between them and the surfaces of the respective rolls, it will collect in the space between a doctor E and the roll above it or below it as the case may be. The doctors may have roughened or serrated surfaces preferably in section like saw-teeth sloped in the direction of travel of the bamboo through the machine whereby a slight drag is imposed on the material to prevent over rapid feeding and also the bamboo is rolled or turned over to present fresh surfaces to be acted upon by the next pair of rolls. One such doctor is shown in Fig. 4.

Assuming that a length of bamboo has not passed through the previous pair of rolls in a direction parallel to the axes of the rolls, it will pass into that space between the doctor and its coacting roll and will be turned into its proper direction by the succeeding length of bamboo and as each succeeding length of bamboo comes into that space, those lengths previously therein will be forced into the "nip" between the next pair of rolls. As the speed of the rolls increases progressively through the machine, as soon as the material has been "nipped" by a pair of them, it will be carried away more quickly than will the material be fed into the "nip" so that no blockage will occur.

The supports or framework of the machine have been shown in the drawings but have not been referred to specifically herein as they may be of any desired type or construction, and although the three parts of the machine have been illustrated as carried in a common framework, they may be

each carried independently and may therefore each be separately adjusted one to the other.

The rolls D¹⁰-D¹⁴ are preferably fluted or serrated in any desired manner and the serrations may have squared, rounded or other edges. They are preferably not parallel to the axes of the rolls but are slightly inclined thereto as shown in the rolls D¹³ and D¹⁴ in Fig. 2. By this means the doctors E may press against them without the risk of buckling or jamming. Other doctors may also be provided to act on the rolls to maintain them in a clean condition.

The drive for the machine will now be described and although the particular ratios of the gears are not specifically detailed they are preferably such as to permit the peripheral speed of each roll to be greater than that of the roll immediately preceding it in the series of rolls, when considered in the direction of travel of the bamboo through the machine, by an amount equal to about 10% of the speed of that preceding roll.

The main shaft F is driven in any convenient manner and has keyed or otherwise secured to it pinions F¹ and F², meshing with gear wheels F³ and F⁴ respectively, the latter being carried on shafts F⁵ and F⁶ respectively. The shaft F⁶ also has keyed or otherwise secured to it a gear wheel F⁷ which in its turn meshes with a gear-wheel F⁸ carried on a shaft F⁹ supporting the reducing feed wheel C and the shaft F⁶ supports the reducing feed wheel C¹. There is also secured to the shaft F⁶ another gear wheel F¹⁰ meshing with the pinion B⁹ carried on the shaft F¹² and the pinion B⁹ meshes, as before described, with the pinion B⁸. The gear-wheel F⁷ also meshes with another gear-wheel F¹³ carried on a shaft F¹⁴ and a gear wheel F¹⁵ on the shaft D intermeshes with the gear wheel F¹³. The drive for the shafts D¹ and D² is effected from a gear-wheel F¹⁶ carried on the shaft F⁵ intermeshing with a gear wheel F¹⁷ on the shaft D¹ which in its turn meshes with a gear-wheel F¹⁸ on the shaft D². The drive for the rolls D¹³ and D¹⁴ is also effected from the shaft F⁵ through a gear-wheel F¹⁹ thereon and gear-wheels F²⁰ and F²¹ carried on the shafts D³ and D⁴ respectively.

The material resulting from the machine consists of substantially separated fibers of practically the same length as that of the bamboo stems introduced into the machine so that when utilized for papermaking or for the production of papermakers' half-stuff or paper pulp, a paper or pulp may be produced having a long fiber which will give strength to the resultant paper.

One embodiment of the invention has been described in detail but modifications may be made, for example, instead of arranging

the rolls in staggered relationship they could be arranged with their axes in the same plane, in which case a doctor E would extend from one roll to a roll next but one to it. Also, the details of the drive may be modified provided that the parts are driven at the required relative speeds.

Throughout the specification the reducing apparatus proper under the third heading 10 has been described as comprising a series of coöperating rolls but these may be replaced by any other members providing surfaces that will coöperate in a similar manner. Hence in the specification and the following 15 claims, where the term roll or rolls has been employed in this connection it is to be understood to cover any such other member or members.

In conjunction with or additionally to the 20 apparatus herein described a cutting appliance of any desired form may be used to cut the separated fibers or separated groups of fibers into suitable lengths for further treatment.

25 Other modifications may be made provided always that the spirit of the invention is not departed from.

What I claim as my invention and desire to secure by Letters Patent is:—

30 1. Apparatus for reducing material of the kind described to separated fibers or separated groups of fibers comprising in combination, a plurality of rotatable rolls adapted in pairs to operate upon the material the 35 two rolls of a pair rotating at different peripheral speeds, feeding means to deliver the culms or stalks to a pair of rolls with the lengths of the stalks parallel or virtually so with the lengths of the rolls, and 40 means to support and guide the material in the interval between the action upon it of two successive pairs of rolls, substantially parallel batches of material being propelled against one another along the face of the 45 supporting guide-member in order to parallelize them.

2. Apparatus for reducing material of the kind described to separated fibers or separated groups of fibers comprising in combination,

50 a plurality of rotatable rolls adapted in pairs to operate upon the material the two rolls of a pair rotating at different peripheral speeds, feeding means to deliver the culms or stalks to a pair of rolls with the lengths of the stalks parallel or virtually so with the lengths of the rolls, means 55 to support and guide the material in the interval between the action upon it of two successive pairs of rolls, successive substantially parallel batches of material being 60 propelled against one another along the face of the supporting guide-member in order to regulate the charges delivered to the reducing apparatus.

3. Apparatus for reducing material of the kind described to separated fibers or separated groups of fibers comprising in combination, a plurality of rotatable rolls adapted in pairs to operate upon the material the two rolls of a pair rotating at different peripheral speeds, feeding means to deliver the culms or stalks to a pair of rolls with the lengths of the stalks parallel or virtually so with the lengths of the rolls, 75 means to support and guide the material in the interval between the action upon it of two successive pairs of rolls, successive substantially parallel batches of material being propelled against one another along the face 80 of the supporting guide-member in order to parallelize them, and a reducing feed having a support for the material and a member co-acting therewith to reduce any depth of material on the support which is over and 85 above a predetermined minimum.

4. Apparatus for reducing material of the kind described to separated fibers or separated groups of fibers comprising in combination, a plurality of rotatable rolls adapted 90 in pairs to operate upon the material the two rolls of a pair rotating at different peripheral speeds, and feeding means to deliver the culms or stalks to a pair of rolls with the lengths of the stalks parallel or virtually so 95 with the lengths of the rolls, the material being parallelized after it has left one pair of rolls and before it is fed to another pair of rolls.

5. Apparatus for reducing material of the kind described to separated fibers or separated groups of fibers comprising in combination, a plurality of rotatable rolls adapted in pairs to operate upon the material the two rolls of a pair rotating at different peripheral speeds, feeding means to deliver the culms or stalks to a pair of rolls with the lengths of the stalks parallel or virtually so with the lengths of the rolls, the material being parallelized after it has left one pair 105 of rolls and before it is fed to another pair 110 of rolls, and a feeder device adapted to regulate the charges which it delivers to the reducing apparatus.

6. Apparatus for reducing material of the kind described to separated fibers or separated groups of fibers comprising in combination, a plurality of rotatable rolls adapted in pairs to operate upon the material, the two rolls of a pair rotating at different peripheral speeds, feeding means to deliver the culms or stalks to a pair of rolls with the lengths of the stalks parallel or virtually so with the lengths of the rolls, and a device 120 adapted to regulate the charges delivered to the reducing apparatus.

7. Apparatus for reducing material of the kind described to separated fibers or separated groups of fibers comprising in combination, a plurality of rotatable rolls adapted 125 130

in pairs to operate upon the material, the two rolls of a pair rotating at different peripheral speeds, feeding means to deliver the culms or stalks to a pair of rolls with the lengths of the stalks parallel or virtually so with the lengths of the rolls, a device adapted to regulate the charges delivered to the reducing apparatus, and means coöperating with the said device and operated by the charge to prevent the delivery of that charge when the quantity thereof exceeds predetermined limits.

8. In an apparatus of the character described, a reducing feed comprising two rotating members whose axes are preferably in different horizontal planes, each of said members having its periphery serrated or channeled parallel to its axis, the serrations in one member providing supporting surfaces for the material, the minimum distance between the centers of rotation of the two members being fixed while movement between the centers in the opposite direction is resiliently controlled.

25 9. Apparatus for reducing material of the kind described to separated fibers or separated groups of fibers comprising a plurality of rotatable rolls adapted to apply a combined rubbing and crushing action to material between adjacent rolls, feeding means to deliver the culms or stalks to a pair of rolls with the lengths of the stalks parallel or virtually so with the lengths of the rolls, and means presenting a serrated 30 surface to the material and adapted to guide it in the interval between the action upon it of two successive pairs of rolls, successive substantially parallel batches of material being propelled against one another along the 35 face of the said serrated guiding member in order to parallelize them.

10. For treating material of the kind described, the combination with apparatus for reducing the material of a device to preliminarily reduce the size of the material, and a conveyer to deliver the material in regulated quantities to the said device, the conveyer and device together arranged to feed the material in regulated and sized 45 quantities to the reducing apparatus.

50 11. Apparatus for reducing material of the kind described to separated fibers or separated groups of fibers comprising two members adapted to receive the material between them, means to cause relative movement between said members to produce a combined rubbing and crushing action to feeder device adapted to regulate the charges which it delivers to the said two 55 members, and means coöperating with the feeder device and operated by a charge to prevent the delivery of that charge when the quantity thereof exceeds predetermined limits.

65 12. Apparatus for reducing material of

the kind described to separated fibers or separated groups of fibers comprising in combination, a plurality of rolls arranged in series and adapted in pairs to apply a combined rubbing and crushing action to virtually all the different portions of the length of the culm or stalk at the same time each of the rolls excepting the two end ones being arranged to coöperate with two others and the peripheral speeds of the rolls increasing progressively through the series.

13. Apparatus for reducing material of the kind described to separated fibers or separated groups of fibers comprising in combination, a plurality of rolls arranged in series and adapted in pairs to apply a combined rubbing and crushing action to virtually all the different portions of the length of the culm or stalk at the same time each of the rolls excepting the two end ones being arranged to coöperate with two others and the peripheral speeds of the rolls increasing progressively through the series, the material being parallelized after it has left one pair of rolls and before it is fed to another pair of rolls so that the lengths of the culms or stalks are parallel or virtually so with the lengths of the rolls.

14. Apparatus for reducing material of the kind described to separated fibers or separated groups of fibers comprising in combination, a plurality of rolls arranged in series and adapted in pairs to apply a combined rubbing and crushing action to virtually all the different portions of the length of the culm or stalk at the same time each of the rolls excepting the two end ones being arranged to coöperate with two others and the peripheral speeds of the rolls increasing progressively through the series, means to support the material in the interval between the action upon it of two successive pairs of rolls upon which means the material is parallelized after it leaves one pair of rolls and before it is fed to the next pair.

15. Apparatus for reducing material of the kind described to separated fibers or separated groups of fibers comprising in combination, a plurality of rolls arranged in series and adapted in pairs to apply a combined rubbing and crushing action to virtually all the different portions of the length of the culm or stalk at the same time each of the rolls excepting the two end ones being arranged to coöperate with two others and the peripheral speeds of the rolls increasing progressively through the series, and a feeder device adapted to regulate the charges which it delivers to the reducing apparatus.

16. A method of reducing material of the kind described to separated fibers or separated groups of fibers which consists in first feeding the stalks laterally reducing to

a predetermined size all those of the culms or stalks which are above that size and then subjecting them to a simultaneous rubbing and crushing action which is applied to virtually all the different portions of the length of the culm or stalk at the same time.

In testimony whereof I have signed my

name to this specification in the presence of two subscribing witnesses.
